SUTURE ROLL DISPENSER

Charles W. Norman, North Plainfield, N.J., assignor to
Ethicon, Inc., a corporation of New Jersey

Filed Jan. 2, 1962, Ser. No. 68,158

Term of patent 14 years

(Cl. D52—1)

Fig. 1.

Fig. 6.

FIGURE 1 is a perspective view of a suture roll dispenser showing my new design;

FIGURE 2 is an edge view of the dispenser looking from the left-hand side of FIGURE 3;

FIGURE 3 is a face view of the dispenser of FIGURE 1 looking to the reverse side;

FIGURE 4 is an edge view of the dispenser looking from the right-hand side of FIGURE 3;

FIGURE 5 is an inverted plan view of FIGURE 3; and

FIGURE 6 is a detailed section taken along the line 6—6 of FIGURE 3.

I claim:

The ornamental design for a suture roll dispenser, as shown.
